UNITED STATES PATENT OFFICE.

HOLGER THEILGAARD, OF CHICAGO, ILLINOIS, ASSIGNOR TO ELECTROGRAPH ADVERTISING SERVICE, OF CHICAGO, ILLINOIS, A CORPORATION OF ILLINOIS.

PRINTING MECHANISM.

Application filed February 2, 1922. Serial No. 533,533.

This invention relates in general to printing presses and addressing machines and the like, and has more particular reference to machines of this character wherein a part 5 of the matter being printed is altered at each printing impression.

The invention has for a principal object the provision of an apparatus which will automatically effect the substitution of a 10 number of linotype slugs or similar printing type within the printing chase after each impression.

My invention contemplates in this regard the equipment of a printing press with an 15 apparatus or instrumentality accomplishing the change mentioned as a part of the text itself so that the substituted characters will print in exact uniformity with the unchanged characters, and all will be of type 20 printing as contradistinguished from typewriter printing, although it will be manifest that simulation of typewriting is well within the purview of the invention, considered from several aspects. The invention is 25 adapted, of course, for varied salutations and addresses as a part of circular letters and dodgers and the like. It has, however, a much wider use, being particularly adapted to change the text of pages within 30 a printed volume without the fact that such change has been made being capable of subsequent detection. As a concrete example of such use, it is possible with a machine embodying my invention to address one or more 35 advertisements in an issue of a magazine individually to the particular subscriber for whom each copy is intended.

Another important object of the invention is the provision of a machine of this 40 character which will be wholly automatic in its action and which will not slow the action of the press to a degree rendering use of the machine impracticable from a commercial standpoint.

45 Numerous other objects and advantages of the invention will be apparent as it is better understood from the following description, which, taken in connection with the accompanying drawings, discloses a preferred embodiment thereof.

Referring to the drawings,

Figure 1 is a side elevation of a machine embodying my present invention;

50 Fig. 2 is a side elevation looking from the opposite side;

Fig. 3 is an end view, taken from the operator's end of the press;

Fig. 4 is a partial enlarged front elevation of the slug feeding mechanism;

Fig. 5 is an enlarged detail of the mechanism for moving the slugs endwise as an incident to the feeding;

Fig. 6 is a partial plan section, taken substantially on the line 6—6 of Fig. 4;

Fig. 7 is a detail section of the magazine 65 pressure release;

Fig. 8 is a section taken substantially at right angles and through the part shown in Fig. 7;

Fig. 9 is a perspective view of a detail 70 of the magazine;

Fig. 10 is a section taken substantially on the line 10—10 of Fig. 4;

Fig. 11 is a view similar to Fig. 10, showing the parts in different relation;

Fig. 12 is a perspective disassembled view of a detail of such mechanism;

Fig. 13 is a fragmentary section similar to Figs. 10 and 11, and showing the parts in still a different relation;

Fig. 14 is a section taken substantially on the line 14—14 of Fig. 4;

Fig. 15 is a section taken substantially on the line 15—15 of Fig. 4;

Fig. 16 is a section through the magazine 85 support, and taken substantially on the line 16—16 of Fig. 17;

Fig. 17 is an enlarged detail partial elevation of the mechanism for swinging the magazine;

Figs. 18 and 19 are sections taken substantially on the lines 18—18 and 19—19 respectively of Fig. 17;

Fig. 20 is an enlarged partial elevation 95 of the upper drive members;

Fig. 21 is a top plan view, the parts being shown in section, of the lower drive members;

Figs. 22 and 23 are sections taken on the lines 22—22 and 23—23 respectively of Fig. 100 21;

Figs. 24 and 25 are sections taken respectively on the lines 24—24 and 25—25 of Fig. 20;

Fig. 26 is a front elevation of the chase 105 showing the chase lifting mechanism;

Fig. 27 is a section taken substantially on the line 27—27 of Fig. 26;

Fig. 28 is a section of the chase lock and 110 release;

Fig. 29 is a perspective view of a slug group; and

Fig. 30 is a section taken substantially on line 30—30 in Fig. 28.

For the purpose of illustrating my present invention, I have shown on the drawings a press in which it is embodied. This press, as selected for the purposes of illustration, is, so far as the ordinary printing parts are concerned, of a well known standard construction. It comprises the frame work 41 carrying the platen 42 which in the printing is adapted to cooperate with the chase support 43, and has the usual inking roll organization 44. The chase support and the inking roll organization are carried in a swinging frame part 45. These parts and other incidental press parts are not thought to require particular description.

I have provided a supplemental frame work 46 which supports the operative mechanisms and devices I have provided for accomplishing the several functions incident to the change of type matter contemplated.

Power is introduced into the apparatus from a pulley 51 upon a shaft 52 (Figs. 1, 2 and 21), this shaft being mounted in bearing standards 53 and 54. A fly wheel 55 is mounted on the end of the shaft and the clutch 56 of any preferred type or construction is positioned for manipulation by a shifting member 57 connected by a rod 58 with a clutch lever 59 pivoted at 61 at the front of the machine. The shaft 52 delivers its power periodically to a shaft 62 in bearings 63 and 64 and continuously to a shaft 65 having bearing at one end in the bracket 54 and 66 and in upper bearings 67 and 68. The shaft 62 drives the printing mechanisms proper, and the shaft 65 the slug changing devices. A shaft 69 has bearing at 71 in the standard 54 and at 72 in the frame of the machine, and carries a gear 73 which meshes with a pinion 74 on the clutch. The shaft 69 is also provided with a pinion 75 meshing with a gear 76 on a shaft 77.

The intermittent drive for the printing parts will be first described. A sleeve 78 is mounted upon the shaft 62 and has rotative bearing at 63. This sleeve is provided with a pinion 79 meshing with the gear 76 so that through the train of gears, just described, continuous rotation is imparted to the pinion 79. The left hand end of the sleeve (viewing Fig. 21) is given a ratchet face 81, and this is adapted for engagement by a cooperating face of a sleeve part 82 splined against independent rotation on the shaft 62 but movable lengthwise thereof. A spring 83 normally pushes the ratchet face into interlocked relation and when interlocked rotation of the shaft 62 of course results. The sleeve member 82 is engaged

by a yoke 84 upon the end of a plunger 85, having sliding bearing in the frame and carrying a roll 86 in engagement with a cam 87 on the side of the gear 76. Viewing Fig. 22, it will be noted that this cam is in the form of a rib, extending throughout an appropriate arc on the adjacent face of the gear, and when the roll 86 rides up on this rib, power is cut off from the shaft 62 by disengagement of the ratchet faces. I provide means for stopping further rotation of the shaft 62. This means comprises a brake drum 88 on the shaft 62 and this brake drum is embraced by a brake band 89 controlled in turn by a brake lever 91 carrying a roll 92, engaging a cam 93 on the shaft 77. It will be understood that the shaft 62 through gears 94 and 95 actuates shaft 96 which is the shaft driving the parts making the printing impression. These parts, as has been stated, are of usual construction and operate in the usual manner when actuated, and so are not shown or described in detail.

It will be noted that the gear 76 rotates continuously. The shaft 77 carries a bevel pinion 101 which engages a bevel pinion 102 on a shaft 103 having bearing at 66. The shaft 103 is enlarged above the bearing and is recessed at 100 to receive the lower end of shaft 65. A clutch sleeve 104 is fixed on shaft 65. Referring to Fig. 1, reference character 105 indicates the usual hand lever for interrupting the printing action without shutting off the power. This lever is schematically shown as connected in the usual fashion to the arm 106 usually accomplishing this function in this type of press. It is also connected by a thrust member 107 with a bell crank 108 for operating the slidable clutch sleeve 104. Interruption therefore, of the printing action is accompanied by like interruption of the slug feeding and substituting mechanisms to be presently described, and which are actuated through the shaft 65.

Referring now to Figs. 4 and 6, the slugs, indicated by reference character 111, are fed down from a slug carrier 112 into a chute 113 by gravity. At the bottom of this chute they are moved endwise or laterally at 114 into a second chute 115, in which the slug groups are spaced apart and intermittently advance by reciprocating dog carrying slides 116 to the magazine indicated generally at 117.

The slug carriers 112 may, if desired, be the storage receptacles for the slugs, and are arrangeable in the inclined operative position, shown in Fig. 4, by inserting the lower end in the top of the chute 113 and resting the upper end upon the support 118.

The slugs are given the endwise movement at 114 by a mechanism to be now described, reference being had more particularly to Figs. 1, 14, 5 and 6. The shaft 65 rotates

a shaft 121 mounted in suitable bearings 122, 123 in the supplemental frame, through a spiral gear 124 on shaft 65, and spiral gear 125 on shaft 121. Shaft 121 carries 5 a bevel pinion 126 at its front end which meshes with a bevel pinion 127 on a vertical shaft 128, this shaft in turn having a bevel pinion 129 on its upper end meshing with a bevel pinion 131 on a cross shaft 132, extending across at the top near the front of 10 said supplemental frame work. This shaft carries a cam 133 engaged by a roller 134 on a lever 135 pivoted at 136 on the frame and provided with a spring 137 to cause the 15 roller to follow the cam. The lower end of the lever 135 is slotted at 130 to engage a pin 140 in a reciprocating rod 138. The rod 138 is suitably guided as at 139 and slides back and forth across and above the slugs. At its 20 forward end it carries a downwardly extending arm 141 which in turn carries an inwardly extending thrust rod 142 having bearing at 143 through the outer chute side, and having at its inner end a pusher head 25 144 adapted to engage the outer slug end and push a group of slugs into the second chute 115.

It may be mentioned at this point that I prefer to secure the individual slugs of a group 30 together, and this may conveniently be done by welding them throughout a confined area, or, throughout a number of confined but distributed areas, as indicated in Fig. 29 by dotted lines 145. This arrangement permits 35 of the use of a greater or less number of slugs without the need of providing delicate selecting and feeding mechanisms, it being merely sufficient that the various passages permit movement of slug groups of greatest 40 dimension and the feeding mechanisms being so constructed and arranged to accurately engage and feed slugs of least dimension.

When a slug group has been moved into 45 chute 115 it is initially advanced, as will be now described, to bring it within the range of action of the dog carrying slides 116, reference being had in this connection to Fig. 6. A cam 151 is mounted upon the 50 shaft 121 and engages a roll 152 upon a lever 153 pivoted at 154 in a bracket 155 extending out from the supplemental frame. This lever is connected by a link 156 with a block or cross head 157, secured to two 55 rods 158 having bearing at 159 and 160. These rods carry a head 195 that is arranged to support one or more rods 196 that are adapted to be projected through apertures 161 just back of the slug group 60 when it is first moved into the chute 115, and upon reciprocation of the rods 158 and 196 under the oscillation of the lever 153, the slug group is advanced to within the zone of action of the dog carrying slides 116.

65 Referring now to Figs. 6 and 14, the

drive for the dog carrying slides will be now described. A cam 166 is mounted upon shaft 121 and this cam is adapted for engagement by a roll 167 on a slide arm 168. The slide arm is slotted to embrace the 70 shaft 121 and carries a second roll 169 adapted for engagement upon the opposite side of a cam 171 companion with cam 166. The slide rod 168 has bearing on the shaft 121 and in a bracket 172, and is connected 75 by a roll 173 in a slot 174 in the end of a lever 175 pivoted at 176 on bracket 155. The lever is connected by a link 177 to an arm 178 (Fig. 14) fast on a rock shaft 179, mounted in bearings 181 extending down 80 beneath the chute 115. This shaft has an arm 182 extending up at each side of the chute and connected by a link 183 with a rod 184 slidable in bearing 185 and engaged by an arm 186 extending out from the side 85 of the adjacent pawl carrying slide 116. This slide carries a number of pawls 187 arranged in spaced relation and adapted to engage behind the slug groups to intermittently advance them, as will be readily understood. Stationary pawls 188 are mounted on side members 189 to prevent the slug groups having any return movement with the slides 116.

The slug groups are thus intermittently 95 advanced and are shoved one by one into a transfer mechanism which conveys them to adjacent the chase. This transfer mechanism and the devices for operating it will now be described, reference being had in 100 this connection to Figs. 6, 10 to 13, 16 and 17. A shaft 191 is mounted in the supplemental frame work and above and inwardly of the chute 115. The magazine 117 contains two pockets 192 and 193, each of a 105 size adapted to contain a slug group. It may be mentioned at this point that the magazine, when in the position shown in Fig. 10, presents the pocket 192 to receive a slug group from the chute 115, and is 110 then swung down to the chase, delivering this slug group into the chase and receiving from it the slug group previously printed. This last mentioned slug group is received in the pocket 193 and brought back for 115 disposal, being shoved into a receiving chute 194 (Fig. 6). The rods 158 are projectible through the pockets 192 and 193 and through a partition 197 (Fig. 7) between them. These rods 158 push the slug group 120 from the pocket 193 into the chute 194 and the slug group being received in the pocket 192 drops upon the rods and is supported until the rods are retracted when the slug group drops to the bottom of the pocket 192. 125

The slug group upon being received in the pocket 192 is held against displacement in the movement of the magazine by a rod 198 (Fig. 8) extending through the magazine wall 199, and arranged beneath the 130

chute 115 when the magazine is up (Figs. 7 and 10). This rod extends through a thimble 201 within which is a spring 202 bearing at one end against the thimble and at the other against a collar 203 on the rod. The outer end of the rod is provided with a pin 204 locking it to a sleeve 205 on the end of the thimble and carrying two rollers 206 adapted to engage a cam 207 to retract the rod when the magazine arrives at the top of its stroke, the cam being located upon the bottom of the chute 115. When the magazine is swung downwardly the rod is moved by the spring 202 into engagement with the side of the slug group in the pocket 192 and holds it in place with a yielding pressure.

The downward movement of the magazine brings the pocket 193 in registration with the slug group contained in the chase, and at this time a gate or closure is disposed across the face of the slug group in the pocket 192. This gate is indicated by reference character 208 (Fig. 11) and is secured to a bracket 209 mounted on the shaft 191 (Fig. 6), this bracket being also held against independent rotation so that the gate and magazine swing together.

The mechanism for swinging the magazine will now be described. A shaft 211 is mounted in horizontal position in bearings 212 and 213, and carries a spiral gear 214 meshing with spiral gear 124 on shaft 65. The shaft 211 is provided with two cams 215 and 216 which engage rolls respectively on a slotted link 217, these rolls being numbered on the drawings 218 and 219. A slot of the link embraces the shaft 211. The link 217 is connected to a gear 221 to rock the same and this gear meshes with a pinion 222 mounted at 223 on the supplemental frame and carrying a pinion 224. The gear 224 engages a gear 225 fast on the end of shaft 191. The action of these gears is a rocking action and I provide means for cushioning the stopping of the gear and shaft at each end of their oscillations. These means comprise a bracket 226 fast on the gear 224 and having projections 227 and 228 at its end. An arm 229 (Fig. 17) is loosely pivoted on the shaft 223 and extended between the projections 227 and 228 and a spring 231 is provided between the arm 229 and the upper projection 227. When the arm 229 swings down in lowering the magazine it engages a stop pin or set screw 232 in a bracket 233 and compressing the spring brings the magazine to accurate position without jar. A similar construction is provided on the gear 225 at 234, except that here two springs 235 and 236 are provided and the arm is cushioned at the end of its movement in each direction, engaging a set screw 237 in the bracket 233 and a set screw 238 in a bracket 239.

The chase is lifted from its bed into a vertical position above the bed to permit the slug transfer. A pair of chase guides 241 are mounted above the chase when the chase is in inking position, and alongside these are guides 242 for the chase lifter. The chase lifter comprises side members 243 (Fig. 26) sliding in the guides 242, and connected by a cross shaft 244. The chase lifter at each side carries a chase engaging and unlocking device, each such device comprising a depending arm 245 having an end 246 adapted to engage a lever 247 pivoted at 248 on the chase in position to release the usual chase locking device 249 pivoted at 250 and having a latch hook 260 for engaging the chase (Fig. 30). The arm 245 is provided also with a stud 251 adapted to enter into an opening 252 in the chase. A sleeve or socket 253 is carried by the arm and in this socket is a spring pressed detent 254 for yieldingly holding the chase connected to the arm 246. The engagement of the chase by the chase lifter is automatic, it being understood that this action occurs as a result of the conjoint movement of the chase lifter and the press bed, the chase lifter going down to receive the chase, and the chase bed finishing its return stroke after printing. The mechanism for raising and lowering the chase lifter will now be described, reference being had in this connection to Figs. 20, 24 and 25. A shaft 261 is mounted in bearings 262 and 263 at the top of the apparatus and carries a bevel pinion 264 meshing with a bevel pinion 265 on shaft 65. The shaft 261 also carries a cam 266 adapted for engagement by a cam roller 267 on the end of an arm 268 of a lever pivoted on a cross shaft 269. The other arm 271 of this lever is formed into two members spaced along the shaft 269 and each connected by a link 272 with the chase lifter already described. The shaft 269 carries a socket 273 in which is mounted an arm 274 carrying the weight 275 to counterbalance the chase. The shaft 261 is located above the shaft 211 and this shaft 211 carries a control cam 276 adapted to engage an arm 277 fixed on shaft 269 to cause the roll 267 to enter the cam groove 266 at the proper instant.

As soon as the magazine and chase are in proper positions the slug group which has previously printed will be pushed from the chase into the pocket 193 of the magazine. Referring to Figs. 10 and 11, a pusher arm 281 is slidably mounted in an arm 282 fixed on the shaft 223. This arm 282 is adapted to be swung down with the magazine into operative position, and as an incident to such swinging the pusher arm 282 is retracted against the force of a spring 283 which normally projects it. This retraction is accomplished by a slide 284 movable in a support 285 and carrying a

head 286 at one end having slots 287 therein, and carrying a roller 288 at the other, bearing against a cam 289 on shaft 211. A lever 291 is pivoted at 292 on the arm 282 and carries a pin 293 positioned through the two members of the head 286, riding in the slot 287. The lower end of the lever 291 has slotted connection with the slide or pusher arm 281 at 294. A spring 295 causes the roll 288 to follow the cam. The action is such that at the proper instant the roller drops into the low point of the cam and the pusher arm 281 moves forward from the back of the chase to push the previously printed slug group into the pocket 193.

During the downward movement of the magazine the gate has been across the pocket 192 and this gate is now moved over to position in front of the pocket 193 and at the same time the magazine is moved over to register the pocket 192 accurately with respect to the space within the chase in which its slug group is to be positioned. The mechanism for moving the gate and the magazine sidewise will now be described. A shaft 303 is mounted above the shaft 191 and has bearing at one end in the supplemental frame and at the other is reduced at 301 to fit into a sleeve 302 in turn having bearing in the supplemental frame. The shaft and sleeve have endwise sliding movement in their bearings. The sleeve 302 carries the bracket 210 adjustably mounted thereon and the shaft 303 is connected by an arm 304 for similar adjustment. A spring 305 embraces the end of the sleeve 302 between the supplemental frame work and a collar 306. The end of the sleeve is engaged by a roll 307 upon the end of a lever 308 pivoted at 309 and carrying a roll 311 (Fig. 1) engaging a cam 312 on shaft 65, the construction and arrangement of the parts being such as to provide the desired sidewise movement of the gate. The shaft 301 (Figs. 14 and 16) is provided with an arm 313 embracing a pin 314 having a head for limiting outward movement of the shaft under the action of a spring 315 fixed to the bracket arm 304 and to the supplemental frame. A roll 316 on the end of a lever 317 pivoted at 318 (Fig. 17) engages the arm 313 (Fig. 16). This lever carries a roll 319 engaging a cam 312 on a shaft 322 (Figs. 17 and 20) mounted in vertical position in a bracket 323 and carrying a bevel pinion 324 which engages a bevel pinion 325 on shaft 261.

After the magazine has been moved into registration for delivery of the slug group to the chase, a plunger 326 carried by the magazine pushes the slug group into printing position. This plunger has free reciprocation in guides 327 and is connected by a pin 328 to an arm 329 pivoted at 331 on the magazine housing. A spring 332 fixed to

the arm and to a bracket 333 normally pulls the arm 329 to retract the plunger. Referring to Fig. 4, it will be noted that a shaft 334 is mounted in a bearing 335 in the supplemental frame and carries a downwardly extending arm 336 upon which is mounted a notched block 337 adapted to engage a pin 338 on the arm 329. This shaft is periodically oscillated to cause projection of the plunger to insert the slug group in the chase. The shaft 334 carries a second arm 339 (Figs. 4 and 17) connected by a thrust link 341 with a slide 342 embracing shaft 322 and following two cams 343 and 344 on said shaft 322.

When a slug group is moved from the chase into the pocket 193 it enters between a pressure member 345 (Fig. 9) carried in an arm 346 pivoted on a stub shaft 347 and the partition 197 of the magazine 117. The pressure member 345 is normally pulled by a spring 348 up across the side open face of the pocket 193. When the magazine is swung up to slug receiving and discharging position (Figs. 3 and 4), the arm 346 engages a cam face 349 and is swung down out of the way to permit the slug group to be pushed into the chute 194. This action occurs by movement of the rods 158, already described.

During the movement between the opposite ends of travel of the magazine 117, the plunger 326 is latched against upward movement by a latch 351 pivoted at 352 on the magazine and normally held in the position shown in Fig. 11, slightly prior to the arrival of the magazine at its uppermost position. The latch 351 is released or moved from engagement with the plunger 326 by engaging the cam end of a latch 353 that is mounted on the supplemental frame at 354 and normally held in the position shown (Fig. 11) by a spring 355, permitting the plunger 326 to rise to the position shown in Fig. 10 to permit of the insertion of a slug group to be delivered to the chase, or the substitution of slug groups. The latch 353 is normally held in the position shown in Fig. 11 by a spring 355 and is moved to the position shown in Fig. 10 as an incident to releasing the latch 351. Movement in this direction during the unlatching action is limited by a pin 361 carried by an arm 356 that is pivoted at 357 in the supplemental frame work. The hooked end of the latch 353 is so formed that when the latch 353 is not supported or reinforced by the pin 361 the latch 351 will move the latch 353 in a counter-clock wise direction against the spring 355 a sufficient distance to allow the latch 351 to engage over the plunger 326, so that when the magazine moves downwardly the latch 351 will by cam action move the latch 353 to a greater extent in a counter-clock-wise direction and become released therefrom. The pin 361 is carried by an arm 356 that is pivoted on a shaft 357 and

carries a roller 358 arranged to engage a cam 359 and to follow the surface thereof, and when the arm 356 is in the position shown (Fig. 10) the pin 361 reinforces the 5 latch 353 or prevents counter-clock-wise movement thereof from the position shown. The surface of the latch 353 adjacent the pin 361 is so tapered that when the arm 356 and pin 361 carried thereby are lowered from the 10 position shown the latch 353 will be permitted to move in a counter-clock-wise direction and from engagement with the latch 351.

A spring 362 that is arranged to engage an arm 363 fastened on the shaft 357 causes 15 the roll 358 to follow the contour of the cam 359. The cam may be formed in any suitable manner to effect any desired downward movement of the arm 356 and the end of the arm carrying the pin 361 is arranged 20 over the magazine 326 so that when the arm moves downwardly in accordance with the contour of the cam 359 it forces the plunger downwardly against the spring 332 attached to the arm 329 to locate a received slug and 25 into position to be engaged by the latch 351, or downwardly to the extent that the hook of the latch 351 may engage thereover substantially as shown (Fig. 11).

The slug groups do not receive the accumulated inking effect produced upon the 30 type fixed in the chase, and on this account I provide a preinking mechanism for inking the slug groups before they receive the ink from the regular press roll. This inking 35 mechanism comprises an ink tank 367 having any usual inking mechanism 368 governed by a link 369 connected to an arm 371 fixed on the shaft 357 and oscillating with it. An ink table 372 is rotated by a pawl 40 373 upon the sleeve 302 engaging in a ratchet 403 on the under side of the ink table. An inking roll 374 is carried in the arms 375 from a rock shaft 376 in the supplemental frame. An arm 377 connected by a link 378 45 with a lever 379 is fast to this rock shaft 376. The lever 379 is pivoted on shaft 357 and a cam 381 is mounted upon the shaft 357. A spring 382 causes the roll 383 on lever 379 to follow the cam 381 and is fixed 50 at one end to the connection between lever 379 and link 378 and at the other, at 384, to the supplemental frame.

The ink employed to preink the slugs is 55 preferably, or may be the ink used in the printing mechanism, and the inking device of the press and for preinking the slugs are of the same general character, so that uniformity of printing action best results.

The slugs when placed in the chase may 60 have varying thickness and are engaged by two spring pressed slides numbered respectively 391 and 392 in Fig. 26. These slides are given the necessary beveled edges to cause them to be retracted by the slugs and 65 to tightly grip them when received. The

slide 392 is carried on rods 393 taking into a block 394 locked in the chase and backed up by springs 395 held in place in the block by plugs 396. The slide 391 is similarly mounted with the rods 397 extending cross-wise in the chase and forced out by springs 398. In each instance the ends of the rods are shouldered at 399 to engage the ends 401 of recesses 402 to limit inward movement of the slides so that they may be in position to receive the slug group. 70

It is thought that the invention and many of its attendant advantages will be understood from the foregoing description, and it will be apparent that various changes may 80 be made in the form, construction and arrangement of the parts without departing from the spirit and scope of the invention or sacrificing all of its material advantages, the form hereinbefore described being merely a 85 preferred embodiment thereof.

I claim:

1. In a printing press, the combination of a bed, a printing chase mounted thereon, means locking said chase to said bed, means 90 unlocking the chase and moving it to a position off the bed, and means substituting a slug group in said chase when so moved.

2. In a printing press, the combination of a bed, a chase mounted thereon, means lifting the chase above the bed, and a device for pushing a part of the type of said chase out of the chase to permit substitution of type. 95

3. In a printing press, the combination of a bed, a chase mounted thereon, a slug carrier movable to adjacent the chase and adapted to convey a slug group to said chase, and means substituting it for a slug group 100 within the chase. 105

4. In a printing press, the combination of printing mechanism, slug groups for printing, and devices for substituting the slug groups in said printing mechanism after impressions, said devices conducting the slug groups through a substantially circular path of movement as an incident to the delivery thereof to and from the printing mechanism. 110

5. In a printing press, the combination of a swinging bed, a chase carried thereby, means substituting in said chase slug groups after each printing impression, and means interrupting the action of the bed to permit such substitution. 115

6. In a printing press, the combination of a bed, a chase carried thereby, means in the press for inserting in said chase a slug group, and means movable against the rear of the chase for removing a slug group. 120

7. In a printing press, the combination of a chase, a chase carrier, means movable from opposite sides of said chase for inserting and removing respectively slug groups in and from said chase. 125

8. In a printing press, the combination of a chase, a chase carrier, means conveying a slug group to adjacent said chase carrier, said means carrying a member for projecting said slug group into said chase. 5
9. In a printing press, the combination of a chase, a chase carrier, slug conveying means movable into a position adjacent the chase for conveying slug groups, means movable from opposite sides of the chase for projecting a slug group from the chase into said slug conveying means and from said conveying means into said chase. 10
10. In a printing press, the combination of a chase, a chase carrier, a slug conveying magazine for moving slugs toward and from said chase, and separate instrumentalities for removing a slug group from the chase into said magazine and from the magazine into said chase. 15
11. In a printing press, the combination of a chase, a chase carrier, a two pocket magazine movable to adjacent the chase, means for removing a slug group in the chase into a said pocket and from the other said pocket into said chase. 20
12. In a printing press, the combination of a chase, a chase carrier, a two pocket magazine movable to adjacent the chase, means for removing a slug group in the chase into a said pocket and from the other said pocket into said chase, together with means for producing relative movement between said chase and magazine to produce successive registration of said pockets with a predetermined part of the chase. 25
13. In a printing press, the combination of a chase, a chase carrier, a two pocket magazine movable to adjacent the chase, means for removing a slug group in the chase into a said pocket and from the other said pocket into said chase, together with means moving the magazine across the chase to produce successive registration of said pockets with a predetermined part of the chase. 30
14. In a printing press, the combination of a chase, a chase carrier, a two pocket magazine movable to adjacent the chase, means for removing a slug group in the chase into a said pocket and from the other said pocket into said chase, and means movable across said pockets to retain the slug groups therein. 35
15. In a printing press, the combination of a chase, a chase carrier, a magazine for conveying a slug group to adjacent a predetermined part of the chase, and means located back of the slug group in said magazine for projecting said slug group into said predetermined part. 40
16. In a printing press, the combination of a chase, a chase carrier, a magazine for arranging a slug group adjacent said chase, an extractor located on the side of the chase 45
- opposite said magazine, and means for inserting a slug group carried by said magazine into said chase. 50
17. In a printing press, the combination of a chase, a chase carrier, a magazine for arranging a slug group adjacent the chase, an extracting and inserting means for taking the slug groups from the chase and for pushing them into said chase. 55
18. In a printing press, a chase, a bed, a magazine for arranging a slug group adjacent a predetermined part of said chase, means for extracting a slug group from the chase and inserting a slug group from said magazine therein, and means for producing relative movement of said chase and bed to permit extraction and insertion of said slug groups. 60
19. In a printing press, a chase, a bed, a chase lifter, a magazine for arranging a slug group adjacent a predetermined part of said chase, and means extracting a slug group from the chase and inserting a slug group from said magazine in place thereof. 65
20. In a printing press, a chase, a chase carrier comprising a chase bed, a chase lifter, a magazine arranging a slug group adjacent said chase when in lifted position, and means substituting a slug group in said chase for one in said magazine. 70
21. In a printing press, the combination of printing mechanism, a feeding mechanism, said feeding mechanism comprising a stack holder for a plurality of slug groups, means feeding slug groups from said magazine in an endwise direction and then in a sidewise direction in spaced relation, and a magazine successively receiving said slug groups and conveying them to said printing mechanism, said magazine carrying a previously printed slug on its return movement. 75
22. In a printing press, the combination of printing mechanism, a feeding mechanism, said feeding mechanism comprising a stack holder for a plurality of slug groups, means feeding slug groups from said stackholder in an endwise direction and then in a sidewise direction in spaced relation, a magazine carrying a previously printed slug on its return movement, and a chute for receiving slug groups from said magazine. 80
23. In a printing press, the combination of a printing mechanism, a slug feeding mechanism, said slug feeding mechanism comprising chutes extending oppositely in the same general direction, a magazine receiving a slug group from one chute, conveying it to said printing mechanism and receiving a slug group from said printing mechanism and returning it to adjacent another chute, and common means for moving said slug groups into and out of said magazine. 85
24. In a printing press, the combination of printing mechanism, a pair of latterly extending slug chutes, a magazine having a 90

5 pocket for receiving slugs from one of said chutes and delivering said slug into the printing mechanism, and a second pocket for receiving slugs from said printing mechanism and returning it to adjacent the other of said chutes.

10 25. In a printing press, the combination of printing mechanism including a main continuously employed group of printing slugs, a slug feeding mechanism for substituting slugs in said printing mechanism after each printing impression, together with separate inking means for preinking said slugs prior to their being fed into said printing mechanism.

20 26. In a printing press, the combination of printing mechanism including a main continuously employed group of printing slugs, a slug feeding mechanism for substituting slugs in said printing mechanism after each printing impression, together with separate inking means for preinking said slugs prior to their being fed into said printing mechanism and with the ink employed in said 25 printing mechanism.

25 27. In a printing press, the combination of printing mechanism, including an inking device, a slug feeding mechanism for substi-

tuting slugs in said printing mechanism after each printing impression, and a separate pre-inking mechanism of the character of the inking mechanism of said printing mechanism for pre-inking said slugs before the action of the inking mechanism of said printing mechanism. 30

35 28. In a printing press, the combination of printing mechanism, and devices for substituting slug groups in said printing mechanism after each impression thereof, said devices including a movable member adapted to be disposed in a horizontal plane to receive a slug to be printed and to discharge a slug previously printed and to be disposed in a vertical plane to receive a previously printed slug from the printing mechanism, 40 and to insert a slug therein to be printed.

45 29. In a printing press, the combination of printing mechanism, slug groups for printing, and devices for substituting the slug groups in said printing mechanism after impressions, said devices conducting the slug groups through a substantially circular path of movement as an incident to the delivery thereof to the printing mechanism. 50

HOLGER THEILGAARD.
